HEN'S NEST

Boniface A. Grasberger, Richmond, Va.

Application January 10, 1939, Serial No. 250,215

4 Claims. (Cl. 119—50)

This invention relates to hens' nests, and has for the primary object the provision of a device of this character which may be easily kept in a sanitary condition and is especially adaptable for use in conjunction with a plurality of similarly constructed nests, preferably arranged in tiers and in any number of tiers and any number of nests to each tier and providing a separation between pens for hens, each nest being automatic 5 in operation, that is, to automatically close on the entrance of a hen from one pen which is desiring to lay and permitting said hen to leave at will to the other pen after laying and the hen leaving said nest brings about automatic reopening 10 of the nest for the next hen desiring to lay, whereby within a short period of time, the hens which are laying will become separated from the hens which are not laying, permitting laying hens to be segregated from hens which are undesirable 15 or non-productive of eggs.

With these and other objects in view, the invention consists in certain novel features of construction, combination and arrangement of parts to be hereinafter more fully described and 20 claimed.

For a complete understanding of my invention, reference is to be had to the following description and accompanying drawings, in which

Figure 1 is a vertical sectional view illustrating 30 a hen's nest constructed in accordance with my invention and showing the same set to receive a hen desiring to lay.

Figure 2 is a view similar to Figure 1 showing the device which has become automatically closed after the entrance of the hen for laying.

Figure 3 is an end view illustrating the rear door of the nest.

Figure 4 is a sectional view taken on the line 4—4 of Figure 2, showing the front door and in 40 a closed position.

Figure 5 is a vertical sectional view illustrating a modified form of my invention.

Figure 6 is a view similar to Figure 5 showing the nest with the doors thereof closed after the 45 entrance of a hen for laying therein.

Figure 7 is a transverse sectional view showing the front door in closed position.

Referring in detail to the drawings, the numeral 5 indicates as in entirety a nest, consisting 50 of vertically arranged front and rear walls 6 and 7, side walls 8 integral with the front and rear walls and top and bottom walls 9 and 10 separable from the front and rear and side walls and each 55 of a plate-like construction projecting beyond the front and rear doors so as to provide rests

adjacent said doors outwardly of the front, rear and side walls. Having the top and bottom walls separable from the front, rear and side walls, will permit the interior of the nest to be easily cleaned so that it may be kept in a sanitary condition. Also this arrangement permits any number of nests to be arranged in superimposed relation, the top wall of one nest forming the bottom wall of the nest thereabove. Also, in the use of this device it is to be understood that any number of nests can be arranged in superimposed relation or in tiers and any number of tiers arranged adjacent to each other with any number of nests in each tier.

When the nests have thus been arranged they 15 are positioned between pens (not shown) for the hens, the front wall being opposite one pen and the rear wall opposite the other pen, the front and rear walls having doorways 11.

A front door 12 is composed of upper and lower 20 sections 13 and 14 hinged together, as shown at 15, and the upper section 13 is hinged on the inner face of the front wall above the doorway of said front wall, as shown at 16. The width of the sections of the front door is slightly greater than 25 the width of the doorway in the front wall so that the front door cannot be shoved outwardly of the nest but may swing inwardly and upwardly.

A rear door 17 is hinged on the outer face of the rear wall 7 just above the upper edge of the 30 doorway of said rear wall and the length thereof is such that the door when in doorway closing position is spaced a limited distance above the lower edge of the doorway to permit ventilation for the nest when both doors are closed and to 35 admit light for the purpose of attracting a hen to the rear doorway after finishing laying.

A flexible element 18 has one end secured to the rear door 17 adjacent its lower edge and extends through the nest and through an opening 40 19 provided in the section 13 of the front door and is secured to the section 14 of the front door, as shown at 20. It is preferable that the flexible element 18 be located closer to one of the side walls than the other so as not to interfere with 45 the hen while in the nest.

In operation, the rear door 17 is in a closed position and the front door is placed in an open position by swinging the lower section 14 upwardly so as to engage with the front wall, as 50 shown in Figure 1, leaving sufficient space between the lower edge of the section 13 and the lower edge of the doorway to permit a hen to pass partly into the nest and on further movement of the hen into the nest the door 12 is moved into 55

a substantially fully open position by the back of the hen and on so doing the section 14 is moved away from the front wall and as the hen clears the front door the section 14 swings downwardly and the front door assumes door-losing position, as shown in Figure 2. The hen is then closed off from the pen which it left and is in seclusion within the nest which adds to the desirability of the nest for the hen to lay in. After the hen has laid the rear doorway being partly open admits sufficient light to attract the hen thereto and the hen pushing on the rear door 17 swings the latter upwardly so that the hen may leave the nest to enter the second pen. The rear door 17 swinging upwardly into dotted line position, as shown in Figure 1, elevates or swings upwardly the front door and at the same time folds the section 14 upwardly toward the section 13 so that on the hen freeing the rear door and the closing of the latter the front door assumes the full line position, as shown in Figure 1, that is, in an open position to admit the next hen for laying. Thus it will be seen that after the nest has been in use between two pens for a period of time the hens that lay become corralled in the pen opposite the rear wall while the non-laying hens remain in the first pen or the pen opposite the front wall, thereby bringing about a segregation of the laying and non-laying hens. Of course, after the nest has been in use for some time and several tests have been made by permitting the laying hens to use the nest and the non-laying hens naturally not using the nest permits the operator then to determine which hens are of no value from the standpoint of producing eggs and are frequently termed "boarders" in the art and, of course, may be disposed of for eating purposes. Also, through the use of the device the hens which are regular layers and the hens which only lay at intervals may be segregated so that the hens laying every day eventually can be kept separately for breeding purposes.

Referring to my modified form of the invention, as shown in Figures 5 to 7, inclusive, the nest proper, indicated in entirety by the character 21, is constructed similarly to the nest proper 5 in the heretofore described form of the invention. Also, the front and rear doors 22 and 23 are similarly constructed to the front and rear doors 12 and 17. In the modified form of the invention, the difference is in the operating means for the front and rear doors 22 and 23. The rear door has pivoted thereto a rod 24 including a pair of sections pivotally connected, as shown at 25, one section being pivoted to the rear door 23, and the other section to an arm 26 secured on the front door 22 or the lower section 27 thereof, as clearly shown in Figure 7. Thus it will be seen that the rod 24 and arm 26 takes the place of the flexible element 18. The front wall intermediate its upper and lower edges and on opposite sides thereof is provided with projections 28 to be engaged by the section 27 for supporting the front door in a partly open position and sufficient to partially admit a hen to the nest so that on the advancement of the hen entirely into the nest the front door will be elevated to the dotted line position so as to free the section 27 from the projections 28 and allow the front door to assume a complete door-closing position as shown in Figure 6. When the hen leaves the nest by way of the rear doorway by pushing the rear door 23 upwardly the front door is folded and swung upwardly until the section

27 engages with the projection 28 thereby resetting the nest for the next hen.

It is believed that the foregoing description, when taken in connection with the drawings will fully set forth the construction and advantages of this invention to those skilled in the art to which such invention relates, so that further detailed description will not be required.

Having thus described my invention, what I claim is:

1. A hen's nest comprising an enclosure having front and rear doorways, a hinged rear door for the rear doorway and adapted to be opened by a hen leaving the enclosure, a hinged front door for said front doorway and including hingedly connected sections, one of which is adapted to engage the enclosure for supporting the door in a partly open position to permit partial admittance of a hen to said enclosure whereby on the full admittance of a hen to said enclosure the hen brings about elevation of said front door from a partly open position and when freed of the hen the door is adapted to assume a full closing position, and means connecting said doors whereby the opening of the rear door by the hen brings about repositioning of the front door in a partly open position.

2. A hen's nest comprising an enclosure having front and rear doorways, a hinged rear door for the rear doorway and adapted to be opened by a hen leaving the enclosure, a hinged front door for said front doorway and including hingedly connected sections, one of which is adapted to engage the enclosure for supporting the door in a partly open position to permit partial admittance of a hen to said enclosure whereby on the full admittance of a hen to said enclosure the hen brings about elevation of said front door from a partly open position and when freed of the hen the front door assumes a full closing position, and a flexible element connected to the rear door and extending freely through one of the sections of the front door and secured to the other section of said front door whereby on the hen opening the rear door the front door will be repositioned in a partly open position.

3. A hen's nest comprising an enclosure having front and rear doorways, a hinged rear door for the rear doorway and adapted to be opened by a hen leaving the enclosure, a hinged front door for said front doorway and includes hingedly connected sections, one of which is adapted to engage the enclosure for supporting the door in a partly open position to permit partial admittance of a hen to said enclosure whereby on the full admittance of a hen to said enclosure the hen brings about elevation of said front door from a partly open position and when freed of the hen the front door assumes a full closing position, a rod including pivotally connected sections with one section pivotally connected to the rear door, an arm secured on one of the sections of the front door and pivotally connected to the other section of said rod whereby on the rear door being opened by a hen the front door will be repositioned to a partly open position.

4. A hen's nest comprising front and rear and side walls integrally connected and said front and rear walls having doorways, top and bottom walls engaging said front, rear and side walls and separable therefrom and projecting beyond the front and rear walls, a rear door hinged on the rear wall and swinging outwardly from the rear wall, a front door hinged on the front wall and swinging inwardly of said front wall and

including hingedly connected sections whereby one of said sections may be positioned to engage the front wall for supporting the front door in a partly open position, and means connecting said doors whereby on the opening of the rear door, said front door is moved thereby into a partly

open position to permit a hen to pass under said front door and on coming in contact with the latter the hen brings about freeing of said front door from the partly open position for assuming a closed position when disengaged from the hen. 5
